TAIL HOLDING MEANS FOR CASTINGS

Application filed May 10, 1929. Serial No. 362,017.

This invention relates to means for holding the tail of a casting, particularly a curved stereotype printing plate, on a part of the mold on which it is cast, after the tail is severed from the plate.

The principal objects of the invention are to provide means for supporting the tail on the cylinder which will act irrespective of the length of the tail until the operator is ready to remove it; to provide means whereby the tail can be released from the support without undue strain on the operator, and to provide these features in a simple, convenient and inexpensive form.

Other objects and advantages of the invention will appear hereinafter.

Reference is to be had to the accompanying drawings in which

Fig. 1 is a plan of a stereotype plate casting mold, showing a plate in position in the mold and a previously cast plate detached from the cylinder with the tail in the position it occupies at that time;

Fig. 2 is a side view of the corresponding parts;

Fig. 3 is a radial sectional view showing the cutting of the tail from the casting;

Fig. 4 is a side view of a part of the cylinder showing the means for holding the tail;

Figs. 5 and 6 are transverse sectional views on enlarged scale on the lines 5—5 and 6—6 respectively of Fig. 4;

Fig. 7 is a view similar to Fig. 6 showing the position of the tail when being released from the core;

Fig. 8 is a view similar to Fig. 5 showing a modification;

Fig. 9 is a view similar to Fig. 7 of the same modification, and

Fig. 10 is a view similar to Fig. 8 showing another modification.

This invention, although capable of more general use, is particularly adapted for use on an automatic machine for casting stereotype plates and cutting the tails therefrom. It is always necessary with such a machine to provide some means for supporting the tail until the operator has time to remove it. It has been customary to hold tails by the use of a couple of special shaped pins in the beveled

end of the cylinder of the mold. This system has limitations, among which is that the pins cannot hold tails which are too short to reach them and in ordinary practice this occurs frequently.

In order to overcome these difficulties, the cylinder 10 which cooperates with the usual back 11 is provided with means, ordinarily located at two diametrical opposite points, for forming the tail in the act of casting the same in such a way as to hold it positively in position at the point at which this means is located. Thus, when the plate is pushed off the cylinder by means of the usual plate pushers 12, the tail which is moved with it will remain against the surface of the cylinder along its longitudinal center, during at least a part of the plate separating operation, and will be detached from this holding means either by the movement of the plate or by a comparatively easy operation by the hands of the operator.

In the form shown in Figs. 4, 5, 6 and 7, the means specified consists of a strip 13 located upon the cylinder in a longitudinal position and substantially throughout the length of the space in which the tail is cast. This strip is provided with undercut portions 14, either continuous, or preferably in the form of notches spaced apart. Between the notches are screw holes for the application of screws 15 for holding the strip on the cylinder. Obviously, the tail T of the plate P will be cast with integral dove-tailed teeth 16 extending into these notches or recesses, which will hold the tail against the cylinder while the plate and tail are being moved back. The effect of this is shown in Fig. 1 and also in Fig. 7.

It will be seen that the tail will cling to the cylinder on account of this strip along its center and that after it is bent far enough by the action of the pushers 12, the teeth 16 will separate from the notches in which they are cast and finally, after the plate is removed, the tail can be detached by the operator grasping its opposite edges and bringing it back a little further beyond the position in which it is left when the plate is

entirely separated from the cylinder. This is comparatively easy for the operator.

When this arrangement is used it leaves the tail fixed and there is no danger of its dropping off, no matter whether it is of full length or otherwise. These teeth 16 positively prevent the slipping of the tail longitudinally of the strip or downwardly along the cylinder.

10 The same principle is involved in the two modifications shown in Figs. 8, 9 and 10. In these cases, no strip has to be formed on the cylinder, but the cylinder 10 is formed with a longitudinal dove-tailed recess 18 occupying the same space as the strip 13, that is, from a point a short distance above the saw cut to the beveled end of the cylinder. Obviously when the first plate is cast, this strip will form an integral dove-tailed projection 19 on the inside of the tail and this projection, being integral, will have practically the same effect as the strip as far as holding the tail on the cylinder is concerned. This also requires little effort for the operator to bend the two sides of the tail further back and break them off of this dove-tailed strip. In this case, the metal in the dove-tailed strip 19 remains on the cylinder but the pouring of each fresh tail fuses its surface and thus welds it to the new tail being cast.

Furthermore, by employing a rather slight undercut bevel at 20 in a recess, as shown in Fig. 10, a wedging action is derived which prevents the tail from dropping but allows the operator to pull off the tail without undue effort. In this case the metal in the slot comes off the cylinder with the tail and a fresh one is cast on each new tail.

It will be seen that in any of the forms shown, the tail is positively held on the cylinder and yet the usual plate and tail pushers 12 are employed to partially separate the tail when the plate is moved off. The tail, however, is still firmly fixed to the cylinder in such a way that it will not drop or slide off even if used on a vertical cylinder and neither half will be detached to slide off sideways in case of a horizontal cylinder. It will also be obvious that the operator has to exert comparatively little effort to separate the tail, either in one or two parts, and discard it in the usual way and that nothing has to be done, in any of these cases, to the strip 13 or the dove-tailed projection 18 in order to get the mold ready for the next cast. This does not involve any material addition to the expense of the machine nor is it likely to necessitate any expense for repairs.

Although I have illustrated and described only a few forms of the invention, I am aware of the fact that other modifications can be made therein by any person skilled in the art without departing from the scope of the invention as expressed in the claims. Therefore, I do not wish to be limited to all the de-

tails of construction herein shown and described, but what I do claim is:—

1. As an article of manufacture, a mold, in which a soft metal casting is to be made, having means thereon for forming an undercut projection on the tail or riser of the casting integral therewith which will hold the tail on the mold part when the plate is being removed. 70

2. As an article of manufacture, a core or cylinder for a mold for casting a stereotype printing plate with its tail, said cylinder having a longitudinal strip thereon provided with undercut recesses into which the metal of the tail will enter and form integral undercut teeth on the tail for the purpose described. 75

3. As an article of manufacture, a cylinder for a stereotype printing plate mold having means longitudinally located within the body of the tail of the plate for forming integral undercut projections on the inside of the tail to hold the tail on the cylinder. 80

4. As an article of manufacture, a cylinder for casting a stereotype printing plate having a longitudinal strip on its surface provided with undercut recesses along its sides into which the metal of the tail can enter during the casting process to form projecting teeth to hold the tail against sliding along the cylinder when the tail is detached from the plate. 90

5. As an article of manufacture, a cylinder for a stereotype plate mold having on diametrically opposite sides thereof dove-tailed grooves extending longitudinally at the centers of the tails of the plates to be cast for receiving the metal of the tail when cast and holding the tail against movement along or around the cylinder after the tail is separated from the plate. 100

6. As an article of manufacture, a mold part having means by which the riser of the casting to be produced will have interengagement with said mold part to hold the riser in position thereon after the rest of the casting is removed. 110

7. The combination with a stereotype plate mold back, a cylinder therefor and plate pushers for separating the plate by its edges free from the cylinder, of means for holding the tail of the cast plate to the cylinder along a longitudinal area when the edges of the tail are separated from the cylinder. 115

In testimony whereof I have hereunto affixed my signature.

HENRY A. WISE WOOD.
